UNITED STATES PATENT OFFICE

103,118

DESIGN FOR A SLIPPER OR SIMILAR ARTICLE OF FOOTWEAR

Jack Meltzer, New York, N. Y.

Application December 1, 1936, Serial No. 66,231

Term of patent 3½ years

To all whom it may concern:

Be it known that I, Jack Meltzer, a citizen of the United States, residing in New York city, county of the Bronx, and State of New York, have invented a new, original, and ornamental Design for a Slipper or Similar Article of Footwear, of which the following is a specification, reference being had to the accompanying drawing, forming part thereof.

Figure 1 is a perspective view of a slipper or similar article of footwear embodying my new design; and

The dominant feature of the present design resides in the ornamental "Tongue" shown in full-lines in the drawing.

I claim:

The ornamental design for a slipper or similar article of footwear substantially as shown and described.

JACK MELTZER.
